UNITED STATES PATENT OFFICE.

SAMUEL T. WHITAKER, OF COLUMBUS, GEORGIA, ASSIGNOR OF FIFTY-ONE PER CENT.
TO RALPH B. SMALL, OF COLUMBUS, GEORGIA.

BOTTLE-CLOSURE ATTACHMENT.

1,346,621.

Specification of Letters Patent. Patented July 13, 1920.

Application filed December 18, 1915. Serial No. 67,657.

To all whom it may concern:

Be it known that I, SAMUEL T. WHITAKER, citizen of the United States, residing at Columbus, in the county of Muscogee and State of Georgia, have invented certain new and useful Improvements in Bottle-Closure Attachments; and I do hereby declare the following to be a full, clear, and exact description of the invention, such as will enable others skilled in the art to which it appertains to make and use the same.

This invention relates to improvements in attachments for bottles, and is directed more particularly to facilitating manipulation of bottle closures of the type commonly known as crimped caps.

The primary object in view is the elimination of the necessity for the individual user to provide himself with a cap removing tool whenever he desires to remove a bottle cap, to which end the invention comprehends the supply of an effective tool with each bottle to be used.

In the accompanying drawing:—

Figure 1 is a perspective view of a fragment of a bottle, with its attachment embodying the features of the present invention, the retaining band of the attachment being also seen in perspective, detached.

Fig. 2 is a similar view of the same, with a slightly modified embodiment of the retaining band.

Figs. 3, 4 and 5 are perspective views of modified forms of retaining bands, detached.

Fig. 6 is a fragmentary perspective view of the principal portion of the bottle provided with a modified embodiment of the invention.

Referring to the drawing by numerals, 1 indicates an ordinary bottle having a neck 2 having its mouth closed by a crimped cap 3. Encircling the neck 2 is a retaining band 4, which may assume various forms as herein-after pointed out, and as seen in Fig. 1 consists of a tapered strip, having at its larger end an opening forming an eye 5. The smaller end of the band 4, when the band is applied on the neck of the bottle, is inserted through the eye 5 and bent to form a hook 6 which retains the band in place. The band is slit lengthwise at 7 and 8 to form three parts, those extending along the edges of the band being offset in one direction while the intermediate one is caused to stand out to form an eye 9 through which a cap remov-

ing instrument is introduced. The instrument itself may assume any appropriate form, but preferably consists of a body formed of a flat strip of metal 10 having its end portions bent at 11 and 12, so as to conform to the enlargement at one end of the neck and a curvature at the other, whereby the instrument is designed to fit snugly along the neck. An outstanding hook 13 is stamped or otherwise formed from the material of the body 10 so as to be adapted to engage under the flange 3 when the tool is being manipulated, at which time one end of the tool rests on the cap and the other end portion is grasped by the hand of the operator. That end of the tool which engages the cap in operation is the upper end of the tool as seen in Fig. 1. The operation of the tool will, of course, be obvious and consists merely of applying the end of the tool against the upper surface of the cap, with the hook 13 engaging under the flange and then prying upward. This operation, of course, is carried out after withdrawal of the tool from the supporting retainer. By the employment of the present invention, bottles supplied with crimped caps will be rendered just as accessible as the old style bottles with the cork stoppers, and the necessity for the user to carry with him a stopper remover is entirely obviated. At the same time, the tool as carried by the bottles offers no appreciable increase in weight or bulk since it is itself of the lightest serviceable material and is so shaped as to occupy space along the neck not adapted for any other use. The hook or prong 13 is also made use of in affording effective retention of the tool since the hook is caused to rest upon an upper edge portion of the retaining band so as to prevent downward movement of the tool, and since the hook is stamped from the material of the tool, the portions of the tool below the engaged portion of the band increase in size so as to prevent upward dislodgment of the tool by accident. By preference, the tool is removed either by straightening the hook 6 and detaching the band and then withdrawing the tool therefrom or else by breaking the band 4 in the first instance.

Where it is desirable to have bottles returned to the factory for reuse, a different form of band is preferably used from that seen in Fig. 1, such for example, as is seen

in Fig. 2, wherein all of the parts are identical with those seen in Fig. 1 except for the structure of the band, and the same reference numerals and description may apply.

5 The retaining band, however, as seen at 4' consists of a coil or partly coiled spring formed preferably of spring wire. In withdrawing the tool from the band 4', it is merely pulled longitudinally therefrom, the 10 band being preferably formed with an offset portion 9' for accommodating the tool before its withdrawal. During the act of withdrawing the tool, the band merely is sprung sufficiently to allow release of the 15 tool, and then springs back to its position closely encircling the neck of the bottle. After the tool has been used, it may be thrown away, and the bottle returned with the band 4' in place. Then when the bottle 20 is refilled, a new tool is introduced into engagement with the offset portion 9'.

The band for retaining the tool may assume a great variety of embodiments without in the least departing from the invention, a few exemplifications being indicated 25 in Figs. 3, 4 and 5.

In Fig. 3 the band 4' is provided with tabs 9^a, 9^a, adapted to be bent about a tool for retaining the same. This band has one 30 of its ends tapered to facilitate introduction through the eye at the other end for facilitating forming a locking hook similar to that seen at 6 in Fig. 1.

In Fig. 4 is seen a similar band 4^b having 35 similar tabs 9^b, but having its terminals exactly like those of band 4.

In Fig. 5 the band 4^c is seen having the depending portion 7^c provided with tool engaging tabs 9^c, 9^c.

40 In Fig. 6 is seen a structure identical with Fig. 1, with the exception of the band, and the same reference numerals and description will apply with this exception. In this structure the band consists of a preferably 45 thin, fine wire wrapped about the neck of the bottle and about the tool 10 for tying the latter to the former, the end of the wire being twisted or otherwise fastened. More than one loop of the wire may be used as 50 preferred, and the tool is firmly held in place by being engaged, as in all the other structures, at its smallest portion, with the cap-flange-engaging hook resting upon the wire.

55 It should be observed that the bend 11 in the tool snugly fits the curvature of the enlargement of the neck 2 and coöperates with

the hook 13 in that the bend prevents the tool from moving upward because of its engagement with the enlargement of the neck, 60 while the hook 13 prevents the tool from moving downward because of its engagement with the band. Thus, the tool is effectively locked in place against accidental dislodgment, and at the same time, the shape 65 of the tool is such as to occupy a minimum amount of space and at a point where the space could not otherwise be effectively utilized.

What I claim is:—

1. The combination with a cap removing tool having a flat body portion with a laterally turned projection at one end, and a crimped cap flange-engaging hook portion projecting from the body in the same direction as said end and in spaced relation thereto, said body portion being reduced in width adjacent said hook portion, of means for securing the cap removing tool to a bottle having a bead at the terminus of its neck, 80 said means comprising a band adapted to surround said bottle neck and engaging the reduced portion of the tool at that side of the hook farthest removed from the bent end thereof, whereby that portion of the cap 85 removing tool including the hook lying between the bead of the bottle neck and the band is held against movement in one direction by said bead and in the other direction by said band.

2. The combination with a crimped cap removing tool having a substantially straight body portion and an outwardly bent end portion and also having an intermediate cap engaging hook extending outwardly and a reduced portion adjacent the hook, the said tool being proportioned to lie within the space surrounding the reduced portion of the neck of a bottle beneath the bead of the neck with the outwardly extending portion of its upper end engaging such bead and said tool being of less length than the neck of the bottle engaged, of a band adapted to encircle the neck of a bottle and to engage the reduced portion of the tool beneath and in contact with the hook for retaining the hook against longitudinal play away from contact with the bottle neck bead.

In testimony whereof I affix my signature in presence of two witnesses.

SAMUEL T. WHITAKER.
